UNITED STATES PATENT OFFICE.

JOSEF LEGJAKY, OF NEW YORK, N. Y., ASSIGNOR TO JOSEPH SEC, OF NEW YORK, N. Y.

METHOD OF COLORING SURFACES.

No Drawing.

Application filed May 13, 1924. Serial No. 712,991.

The general object of the present invention is to provide a novel and effective method for producing decorative designs in color on paper, cloth, leather and other surfaces.

In a simple and practically desirable mode of carrying out my invention, I form the decorative design on a surface which has a suitable color to form a background for 10 the design by spraying the design outlining color with an air brush onto the surface through a stencil-like body formed by the foliage end or tip of a branch of arbor-vitæ, the arbor-vitæ branch being moved from one 15 location to another over the surface to produce suitably disposed repetitions of the figure or design formed by spraying the color through the branch in any one location of the latter. Pleasing and attractive designs may 20 be formed in the manner described by means of a single color when the surface is initially white or of some suitable plain color, a suitably plain color being one which is comparatively light or bright and which presents 25 sufficient contrast to the color sprayed through the arbor-vitæ branch.

A richer color effect and greater body to the design may be secured and an additional color effect obtained by giving the surface 30 to be decorated a preliminary variegated color effect. To create this variegated initial color effect in practice, I preferably spray a light color onto the surface through a stencil-like body similar to that first described and 35 moved from one location to another over the surface as the initial color is applied so that the figure or design formed is repeated at suitable intervals over the surface. Advantageously the figures thus formed are so 40 spaced apart as to leave uncolored portions of the surface between the figures which may be comparably in size with, but preferably are somewhat smaller than the figures. When proceeding in this manner the final 45 color applied to the surface is preferably stronger than that employed in producing the variegated background, and in spraying the final color through the arbor-vitæ branch the latter is held over the surface in positions 50 each located mainly above an uncolored space between the figures originally formed, but with portions of the branch overlapping the first formed figures.

By proceeding in the manner last described, I am able to produce in the second color application, a pleasing reproduction of

the pattern of the branch employed in the second color application with the design thus formed outlined mainly by the second color, but also tinted and seemingly outlined in 60 part by the color first applied, and in part in the original color of the surface. Advantageously, of course, the three colors are chosen to give pleasantly blending and contrasting effects, and in general the original 65 color and the color first applied should be appreciably lighter colors than the color last applied. The application as described of the two colors to a surface originally white or of some other suitable plain color gives not only 70 an additional color effect, but a depth and richness to the design produced by the final color which is not obtainable by the application of that color alone in the manner first described, to a white surface or one having a 75 uniform color.

Decorative effects may be produced in accordance with the present invention on a surface which like ordinary white paper can have multicolor designs printed thereon by 80 known processes in practical use, but the invention is of especial utility because with it attractive decorative effects may be formed on material such as bookbinder's cloth, 85 leather, imitation leather and wood on which colored designs cannot be applied readily and inexpensively, if at all, by ordinary commercial processes.

In lieu of using a branch of arbor-vitæ to outline the design imparted to the surface 90 decorated, I may use other forms of vegetation such as the leaves of certain ferns, and dried and pressed flowers or foliage. The use of a green branch of arbor-vitæ possesses certain special advantages particularly because of its natural flat shape, its strength and the fact that it has sufficient weight to avoid the displacement of the branch by the impact of the color particles without requiring special care in the manipulation of the air brush by which the color is applied. A single branch of arbor-vitæ can be used repeatedly without drying or cleaning in the course of such use so that a large number of 95 repetitions of the same figure can readily be produced in rapid sequence. In practice the stem of the arbor-vitæ branch may be lightly pressed against the paper by one hand of the operator who manipulates the air brush. 100 As soon as one finger is thus formed, the branch is lifted from the surface and again placed thereon in position for the production 105 110

of another figure. If, and when desirable the branch after some use may be cleaned by dipping it into a suitable solvent and may then be used again. This is not ordinarily 5 desirable with arbor-vitæ branches in practice however, owing to the ease and cheapness with which fresh branches of the proper size and configuration may be obtained. Ordinarily the arbor-vitæ branches are flat 10 enough to require no preliminary pressing or shaping to fit them for use.

Various color agents may be employed in the practice of my invention, the color selected depending on the character of the material to be decorated, the relative cost of 15 different color agents and the color effect desired. In applying color to bookbinder's cloth, paper, leather, imitation leather or wood, I may advantageously employ the 20 waterproof colors formed by dissolving aniline dyes in alcohol, or in some cases I may use water colors. In decorating silk cloth I may use the wood dyes formed from leg-

wood, fustic, or red wood, or may use the so-called batik aniline dyes. In general it is 25 not necessary to apply sizing to the surface to be decorated or to subject the latter to any other special preparatory treatment.

Having now described my invention what I claim as new and desire to secure by Letters Patent, is:

The method of decorating a surface which consists in spraying a color onto spaced apart portions of said surface through the interstices between the portions of the foliage edge tip of a branch of arbor-vitæ, and then spraying a second color on said surface through a similar branch disposed mainly above portions of the surface not colored by the color first applied but in part overlapping the portions colored in the first color application.

Signed at New York city in the county of New York and State of New York this 12th day of May, A. D. 1924.

JOSEF LECJAKY.
